Primary Examiner — John R Yeh(74) *Attorney, Agent, or Firm* — McGarry Bair PC**CLAIM**

The ornamental design for a laundry chemistry dispenser, as
shown and described.

DESCRIPTION

FIG. 1 is a top perspective view of a laundry chemistry
dispenser, showing our new design;

FIG. 2 is a bottom perspective view of the laundry chemistry
dispenser of FIG. 1;

FIG. 3 is a top view of the laundry chemistry dispenser of
FIG. 1;

FIG. 4 is a bottom view of the laundry chemistry dispenser
of FIG. 1;

FIG. 5 is a front view of the laundry chemistry dispenser of
FIG. 1;

FIG. 6 is a rear view of the laundry chemistry dispenser of
FIG. 1;

FIG. 7 is a left side view of the laundry chemistry dispenser
of FIG. 1; and,

FIG. 8 is a right side view of the laundry chemistry dispenser
of FIG. 1.

Portions of the laundry chemistry dispenser shown in broken
lines form no part of the claimed design.

1 Claim, 7 Drawing Sheets(56)
